UNITED STATES PATENT OFFICE.

HORACE RESLEY, OF CUMBERLAND, MARYLAND.

FIRE-ESCAPE.

SPECIFICATION forming part of Letters Patent No. 295,430, dated March 18, 1884.

Application filed May 25, 1883. (No model.)

To all whom it may concern:

Be it known that I, HORACE RESLEY, of Cumberland, in the county of Alleghany and State of Maryland, have invented certain new and useful Improvements in Fire-Escapes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a building provided with my improved fire-escape. Fig. 15 2 is a vertical cross-section of the rail and its bracket. Fig. 3 is a detail view of one of the brackets supporting the rail. Fig. 4 is a perspective detail view of the cage. Fig. 5 is a view of the side of the cage facing the building; and Fig. 6 is a side view of the cage.

Similar letters of reference indicate corresponding parts in all the figures.

My invention has relation to hoisting fire-escapes; and it consists in the improved construction, combination, and arrangement of parts of the same, as hereinafter more fully described and claimed.

In the accompanying drawings, the letter A indicates the outside of a building, to the upper portion of which, under the cornice, is secured a rail, B, by means of brackets C, inserted into the wall of the building. The rail consists of a strip of stout sheet metal, the upper edge or flange of which is turned over, forming a downturned flange, D, which is turned over the T-heads E upon the upper ends of the brackets, fitting tightly over the same. The brackets consist of strong bars of iron, bent in double-L shape, and their upper ends form the cross-heads or T-heads E, while their downward bent ends are secured inside the wall by anchors F, their horizontal portions passing through the wall. Upon this rail rides a pulley, G, journaled in a frame or block, H, the upper end of which passes over and straddles the pulley and forms a hook, I, upon its downward bent end, which catches in under the inner flange of the rail, while its lower end forms a frame or double block, J, 45 in which two pulleys or sheaves, K, are journaled. Two ropes or chains, L, pass over and

are wound around these pulleys, and the cage M is attached to the ends of these ropes, and may be raised or lowered by means of the same. This cage consists of a rectangular casing of wire-netting covered with sheet metal or any other suitable material, and is provided at its upper end with a frame, N, consisting of four or more iron rods connected by one or more rings, O, to which the rope is attached. To the upper end of the outer wall of the cage, which is provided upon its inner side with inward opening doors P, is an outward-projecting arm or bracket, Q, to the outer end of which a rope or chain, R, is attached, while two or more ropes or chains, S, are attached to the lower edge of the same, which serve to draw the cage down from the building when it has been hoisted up.

By the foregoing description, taken in connection with the accompanying drawings, the operation of the escape will be easily understood.

When the escape is to be used, the cage may be hoisted to any story of the building, and may be drawn on the rail from one window to the other in any of the stories of the building by the ropes at its lower end, while the rope attached to the outward-extending bracket serves to force the lower end of the cage in 80 toward the wall, so as to make it safe for persons to enter the cage and prevent accidents, and the inward opening doors prevent persons from falling out of the cage and make it easier for them to enter the cage from the windows.

It will be seen that the construction of the rail and its mode of attachment to the brackets make a very strong and easily-constructed rail, and that the pulley-frame is prevented from slipping from the rail by the hook upon its downward bent end.

Having thus described my invention, I claim and desire to secure by Letters Patent of the United States—

1. In a fire-escape of the described class, the rail formed of a strip of stout sheet metal and bent at its upper portion to form a downward-bent flange adapted to straddle the upper ends of the projecting brackets and fit tightly upon them, as and for the purpose shown and set forth.

2. In a fire-escape of the described class, the combination of the rail, formed by a strip of sheet metal doubled to form a downward-bent flange, as described, with the brackets, 5 consisting of bars of iron bent in double-L shape, inserted into the wall with their horizontal portion, and secured by anchors to the inside of the same at their inner downward-turned ends, and forming T-heads or cross-10 heads upon their outer upward-turned ends, as and for the purpose shown and set forth.
3. In a fire-escape of the described class, the combination of the rail, having inward and downward turned flange, with the pulley-15 frame, having the upper portion bent inward and downward, forming bearings for the pulley riding upon the rail, and bent inward to form a hook catching in under the flange of the rail, as and for the purpose shown and set 20 forth.
4. The herein-described fire-escape, consist-

ing in the rail having inward and downward turned flange, the double-L-shaped brackets, the pulley-frame, having inward-bent hook upon its downward-turned upper end, and 25 having the pulley riding the rail and the hoisting-pulleys journaled in it, the hoisting-ropes, the cage having the outward-extending bracket upon the upper edge of its outer side, the inward-opening doors, and the top frame, and 30 the guide-ropes attached to the lower edge of the cage and to the bracket, all constructed, combined, and arranged to operate as and for the purpose shown and set forth.

In testimony that I claim the foregoing as 35 my own I have hereunto affixed my signature in presence of two witnesses.

HORACE RESLEY.
